UNITED STATES PATENT OFFICE.

JOHN L. DAWES, OF PITTSBURG, PENNSYLVANIA.

DESIGN FOR A BOTTLE.

SPECIFICATION forming part of Design No. 24,956, dated December 10, 1895.

Application filed October 15, 1895. Serial No. 565,802. Term of patent 14 years.

To all whom it may concern:

Be it known that I, JOHN L. DAWES, a resident of Pittsburgh, in the county of Allegheny and State of Pennsylvania, have invented a new and original Design for Bottles; and I do hereby declare the following to be a full, clear, and exact description thereof, reference being had to the accompanying drawings, in which—

- Figure 1 is a front elevation of a bottle embodying the design. Fig. 2 is a side elevation of the same; and Fig. 3 is a horizontal section on the line 3 3, Fig. 1.

The leading features of my design consist in a bottle having a neck, a round or circular body portion tapering outwardly from the neck down to the bottom, and a recess formed on the front of the bottle within the body portion having its sides conforming to the outside shape of the bottle.

A represents the body portion having the neck *b* above the same. The outside of the body portion of the bottle is gradually tapering from the neck *b* down to the bottom *c* of the bottle as at *d*. A recess *e* is formed within the body portion *A* of the bottle, having its sides *f* conforming to the tapered outside *d* of the body portion *A* of the bottle.

I claim—

The design for a bottle, substantially as 30 herein shown and described.

In testimony whereof I, the said JOHN L. DAWES, have hereunto set my hand.

JOHN L. DAWES.

Witnesses:

W. A. BLAKELEY,
J. N. COOKE.
